PRACTICE ATTACHMENT FOR GOLF CLUBS

Joseph B. Sloan, Racine, Wis.

Application January 5, 1951, Serial No. 204,573

2 Claims. (Cl. 273—35)

1

This invention relates to improvements in golf practice devices, and more particularly to an attachment for golf clubs of conventional form for teaching the correct manner of swinging a club to hit a ball squarely without slicing or hooking in regular play.

The device of the present invention utilizes the same principles embodied in the golf practice club disclosed in my copending application bearing Serial Number 184,077, filed September 9, 1950, excepting that the device of the present invention is especially designed for attachment to a conventional golf club instead of requiring a special form of golf club.

My invention is based primarily upon the conception generally accepted by those familiar with the game of golf that to propel a ball in a straight line it should be struck by the club head while the latter is moving in a path with the club face exposed at a right angle to the desired line of flight and without cutting across the ball from "inside out" or from "outside in." Therefore, most golf professionals endeavor to teach the player to perfect a uniform path or arc of swing of the golf club for regular play, wherein the face of the club head meets the ball at right angles and is swung through a substantially elongated arc of several inches immediately before and after impact.

In carrying out the present invention, I provide a novel form of auxiliary head which can be readily attached to the head of a standard or conventional golf club whereby the player can, under guidance of competent instructions, readily develop a most effective, properly "grooved" golf swing for expert play.

The invention may best be understood by reference to the accompanying drawings, in which:

Figure 1 is a perspective view of my novel device, showing it attached to the head of a conventional golf club;

Figure 2 is an enlarged detailed perspective view of the attachment removed from the golf club;

Figure 3 is a front face view of the attachment applied to the golf club, and showing the manner in which the device is used to span a practice golf ball;

Figure 4 is a top plan view of the device shown in Figure 2;

Figure 5 is an illustrative diagram indicating the manner in which the device should be swung with relation to a practice golf ball in making a proper golf shot.

Referring now to details of the embodiment of

my invention illustrated in the drawings, the practice device indicated generally at 10 consists essentially of an auxiliary head having two elongated parallel, upright blades 12 and 13 and a transverse bridge member 14 adapted for detachable connection to the under face of a conventional golf club head, indicated at 15.

In the form shown herein, the blades and bridge member are made of a single piece of perforated sheet metal bent in inverted U-shaped form in cross section, as shown in Figure 3. The blades extend in tapering form toward one end of the device, which may be considered the rear end thereof. The two blades have outwardly extending flanges 16 along their bottom edges where they engage the ground, said flanges being substantially straight throughout the major portion of their length, but said flanges being curved upwardly at the front ends of the blades, as indicated at 17.

As will be seen from Figures 3, 4 and 5, the blades 12 and 13 are spaced apart a distance slightly greater than the diameter of a standard golf ball, indicated at A, and the bridge member 14 spans the blades at a height above the bottom edges of the latter a distance slightly greater than the diameter of the ball, thus forming an open channel, indicated generally at B, along the under face of the device sufficient to clear a golf ball or object of similar size and shape, either when the ball A or equivalent practice object, is resting on the ground, as shown in full lines in Figure 3, or is slightly elevated as on a tee shown dotted in Figure 3.

The means for detachably connecting the device to the under face of a golf club head includes a seating plate 20 which may be fixed to the upper face of the bridge member 14 to form a part thereof. The seating plate is of suitable shape to fit the particular type of club head with which the device is to be employed. In the form shown in the several figures, the device is especially adapted for attachment to a driver 15 and, for this purpose, the seating plate has an upwardly turned flange 21 along its front edge adapted to form an abutment for the striking face 22 of the club head. In addition, the seating plate has an inwardly projecting extension 23 curved upwardly toward its extremity of such shape that the heel 24 of the club head may be nested thereagainst when the club head is in seated relation with respect to the practice device. The seating plate 20 and the curved extension 23 thus form stops to position the center of the striking face 22 of the golf club substan-

tially in vertical alignment above the center of the open channel B, and at right angles thereto.

It will be manifest that the seating plate may be modified to accommodate club heads of any other kind, such as conventional playing irons and putters.

Any suitable securing means for the device may be provided, in the preferred form shown such means consisting of a relatively short length of strap 25 which may be passed beneath the bridge member lengthwise of the device and upwardly around the flange 21 at the front end of the seating plate and thence over and around the upper surface of the club head, as shown in Figures 1 and 3, and finally secured by a buckle 26 of any suitable form. One advantage of using a strap of this kind is that it does not tend to mar the finished surfaces of a club head.

Since the insertion of the practice device between the bottom of a club head and the ground tends to elevate the club head slightly from its normal striking level, the inner blade 13 of the device nearest the heel of the club is preferably made of slightly less height than the outer blade 12, as shown in Figure 3.

In the form shown herein, the blades, bridge member and seating plate are all made of perforated sheet metal which has been found satisfactory for the purpose although other material, such as molded plastic or heavy fiber, can also be used, in whole or in part.

Referring now more particularly to the preferred dimensions of the blades 12 and 13 for carrying out the objects of my invention, I find that, when the device is intended for use with the longer shafted clubs, such as a driver or brassie, the blades are preferably about 6 to 8 inches in length, should be spaced apart about 2 to 2½ inches from each other, and be about 2 to 2½ inches high. For use on conventional clubs of shorter lengths, and hence having a somewhat shorter normal swinging arc, the blades may be made correspondingly shorter in length; although in the case of use with a putter, it may be desirable to make the blades as long or even longer than the blades designed for use with a driver, particularly in cases where the player desires to perfect a putting stroke with a relatively long, straight follow-through. It will be understood, however, that the dimensions above mentioned are not particularly critical and may be varied to suit the needs of the player.

The use and advantages of a practice device made in accordance with my invention will be manifest from the foregoing description. The practice device is attached to the head of a standard club in the manner described; the club is used in the manner indicated diagrammatically in Figure 5 wherein the practice ball, indicated at A, should be swung at by the player with the object of missing the ball completely. In order to accomplish this, it is essential that the club head be swung in a relatively wide arc and with the blades 12 and 13 moving in the same direction as the desired flight of the ball through a distance 65

substantially as great as the length of said blades; otherwise, should the club head be turned at even a slight angle to the desired line of flight, the object ball A will be contacted or struck by one or the other of the blades so as to indicate to the player that his swing has been improperly executed.

Although the practice ball or object A may consist of a conventional golf ball, for best results 10 a practice ball of the same size but made of wool, cotton, plastic or similar material commonly employed for making practice shots will be found preferable, since such balls travel but a limited 15 distance as compared with conventional balls and also are not so subject to damage or injury.

After a player becomes accustomed to the use 20 of my improved form of practice device with his golf club, he will soon learn to recognize and correct mistakes in his golf swing by noting characteristic behaviors of the practice ball when the swing is made improperly so as to strike the ball with one blade of the practice device or the other, as the case may be.

Although I have shown and described certain 25 embodiments of my invention, it will be understood that I do not wish to be limited to the exact construction as described but that various changes or modifications may be made without departing from the spirit or scope of the invention as defined in the appended claims.

I claim:

1. A golf practice device for conventional golf clubs, consisting of an auxiliary head generally U-shaped in cross section with a bridge member and depending parallel blades with continuous ground engaging bottom edges forming an open elongated groove along the under face of said head of sufficient width and height to clear an object of substantially the same diameter as a conventional golf ball when the latter is in normal playing position relative to the ground, and means on said bridge member affording detachable interfitting engagement with the head of a conventional golf club.

2. A device in accordance with claim 1, wherein the means affording detachable engagement with a golf club includes an upstanding stop for receiving the front face of the golf club, and a laterally extending stop for positioning the striking face of the club head substantially in vertical alignment over and at right angles to the groove along the under face of the auxiliary head.

JOSEPH B. SLOAN.
